Primary Examiner — Cynthia Ramirez**(74) Attorney, Agent, or Firm** — Ziolkowski Patent Solutions Group, SC**CLAIM**

The ornamental design for a loading device, as shown and described.

DESCRIPTION

FIG. 1 is a perspective view of a loading device in accordance with the present invention.

FIG. 2 is a front view thereof;

FIG. 3 is a back view thereof;

FIG. 4 is a side view thereof;

FIG. 5 is a top view thereof; and,

FIG. 6 is a bottom view thereof.

The broken lines in the drawing views are included for the purpose of illustrating portions of the loading device that form no part of the claimed design.
